[57]

CLAIM

The ornamental design for a lid for storage container, as shown and described.

DESCRIPTION

FIG. 1 is a top right front perspective view of a lid for storage container showing our new design;

FIG. 2 is a top plan view thereof;

FIG. 3 is a right side elevational view thereof; the left side elevational view being a mirror image;

FIG. 4 is a front elevational view thereof; the rear elevational view being a mirror image; and,

FIG. 5 is a bottom plan view thereof.

The broken line showing of small recessed circles is for illustrative purposes only and forms no part of the claimed design.

1 Claim, 4 Drawing Sheets
